UNITED STATES PATENT OFFICE.

LUCIEN M. KILBURN, OF COUNCIL BLUFFS, IOWA, AND SCOTT VAN ETEN,
OF OMAHA, NEBRASKA.

ELECTRIC GAS-LIGHTER.

SPECIFICATION forming part of Letters Patent No. 488,012, dated December 13, 1892.

Application filed March 21, 1892. Serial No. 425,806. (No model.)

To all whom it may concern:

Be it known that we, LUCIEN M. KILBURN, residing at Council Bluffs, in the county of Pottawattamie, State of Iowa, and SCOTT VAN ETEN, residing at Omaha, in the county of Douglas, State of Nebraska, have invented certain new and useful Improvements in Automatic Gas-Lighters, of which the following is a specification.

10 Our invention relates to that class of automatic electric gas lighting and extinguishing burners in which an oscillating gas-valve in the gas-tube is opened and closed by means of armatures and levers operated by means 15 of electro-magnets, and in which an electric-sparking device is used to ignite the gas when the valve is turned to allow the gas to escape. The objects of our improvements are, first, to provide a burner constructed to have 20 greater efficiency, capacity, and certainty in its operation than any now in use; second, to utilize the electro-mechanical action to the best advantage in its application to moving levers to operate said gas-valve and spark 25 device; third, to obviate all danger of leakage of the gas through said valve and burner; fourth, to construct a burner in which electro-magnets having long range of movement are utilized to move armatures and levers to operate 30 said valve and sparking device.

With other minor objects in view our invention consists in the peculiar combination and arrangement of parts, all of which will be fully described in the specification, and 35 pointed out in the claims, reference being had to the accompanying drawings, in which—

Figure 1 is a side view of our improvement as seen from the valve-operating side. Fig. 2 is a similar view as seen from the opposite 40 side. Fig. 3 is a similar view at right angles to Figs. 1 and 2. Fig. 4 is a perspective detail view of one of the electro-magnet cores. Fig. 5 is an enlarged side view of the base of the valve and the operating-levers; and Fig. 45 6 is a detail perspective view of one of the armatures and its supporting-levers.

Referring to the accompanying drawings, A A² indicate the electro-magnets, which have the peculiar elongated curved and flattened 50 poles B, the inner curved faces of which are

the arcs of a circle, whose center is below the center of the end of the valve E, the peculiar form of such cores or poles being clearly shown in Figs. 1 and 5.

The armatures C C² are attached to the levers D D² X X², independently suspended at their upper end upon the removable pins forming polar projections of the axis of the valve E, and such levers are the radii of a circle of which the point at the center of end 55 of valve E is the center and the faces of the armatures C C² are arcs. When the electro-magnet A is energized, it raises the armature C in an upward circular direction (in opposition to gravity) and brings the lever D in indirect contact with a projecting pin M on the valve E through the medium of a yielding contact, preferably a spring S, as shown, which operation serves to rotate the valve E through a definite arc and bringing its aperture in 60 65 register with the escape-opening in the gas-tube T, thereby allowing the gas to escape.

Z indicates the fixed electrode, and U the movable electrode, which is held for vertical movement in guides on the face of the burner-tube, and which is normally held in contact with electrode Z, through the medium of a spring u. By reference to Fig. 2 it will be 70 75 seen that the lower end of the arm or electrode U projects down and rests normally in the path of the swinging lever X, which lever when the armature C is raised, as before described, serves to raise the electrode-arm U vertically, thereby separating the contacts and producing a spark which ignites the gas, this 80 85 operation of the armatures and levers being automatically repeated as often as an electric current passes through the magnet A and the contacts of the electrodes. When the electro-magnet A² is energized, the armature 90 C² is drawn up in the same manner as above described for the armature C, which operation brings the lever D² in indirect contact through the spring S' with the pin M² on the valve E, and arranged diametrically opposite 95 the pin M, and thereby rotating the valve in a reverse direction back to its normal or closed position and shutting off the gas.

It will be noticed from the foregoing that when the armatures C C² are operated they 100

describe an arc of the same circle, the limit-
ing-points of which are the gas-tube T, against
which they normally rest, and the flange O,
which they strike when drawn up to the ex-
tremities of the poles D of the magnets A A²,
such points being covered with felt or other
suitable material to deaden the sound. In
the levers D D² the pin at the center of the
valve E is their fulcrum, the projecting pins
M M² the weight, and the armatures C C² the
power, thus making the power from the arma-
tures to the center-pin and the weight-arm
from pins M M² to the same pin. The object
of the levers X X² is to form an equal support
for the armatures at each end, though the
lever X acts as a positive lever for elevating
the arm U to produce the spark. The pro-
jections M M² on the base of the valve E are
so arranged that when the levers D D² are
raised by the armatures, one at a time, such
levers act on the said projections to alternately
open and close the valve, and by providing
the spring-contacts S S' allows for a gradual
application of the upward pull of said levers,
the pins M M², and the valve E, thus allow-
ing the armatures and their levers to gain
sufficient momentum to easily overcome the
inertia and initiatory friction of the valve
and arm U, and also when the armatures and
their levers have attained their full range of
movement to rotate the valve a little farther
by restoring the energy imparted to the said
springs by compression at the commencement
of movement. If desired, the springs may be
omitted.

The above-described construction of elec-
tro-magnets, armatures, levers, supports, and
pivots is such as to secure a long mechanical
movement of the armatures, the magnetic at-
traction being the greatest at their normal
position and gradually decreasing in amount
as the armatures are raised, thus allowing the
armatures to start in an advantageous pos-
ition, and also rendering the pull on them
practically uniform during their entire range
of movement.

Having thus described our invention, what
we claim, and desire to secure by Letters Pat-
ent, is—

50. 1. In an automatic electric gas lighter and
extinguisher, in combination, an oscillating
gas-valve, two independently-acting arma-
tures, levers pivotally suspended from and by
polar projections of the axis of said gas-valve,
55 one armature and lever acting to open the
gas-valve and operate the sparking device,
the other armature and lever acting to close

said valve, two independently-excitible elec-
tro-magnets, one to operate each of said ar-
matures and levers, said electro-magnets hav- 60
ing long curved poles of the form described
and shown, as and for the purpose set forth.

2. An automatic electric gas-lighter com-
prising a cut-off valve, the lighting and ex-
tinguishing electro-magnets, their polar ex- 65
tensions having their inner faces curved on
an arc eccentric to the axis of the valve, ar-
matures independently suspended from axial
extensions on the valve and having their
outer contact-faces curved on an arc concen- 70
tric to the valve-axis, substantially as and
for the purpose described.

3. The combination, with tube T, the mag-
nets A A², the valve E, the armatures C C²,
the armature supports or levers D D² X X²,
the fixed electrode Z, the movable electrode
U, having its lower end arranged to be en-
gaged by the swinging lever X, said valve E
having diametrically - oppositely - arranged
projections M M², all arranged substantially 80
as shown, whereby the alternate energizing
of the magnets A A² will alternately rock the
valve to open up and close off the gas-supply
and operate the spark-electrode U, as set
forth. 85

4. The combination, in an electric gas-
lighter of the kind described, the rotatable
valve, the alternately-operated electro-mag-
nets having their poles extended and curved
on their inner face, swinging armatures inde- 90
pendently suspended on the axial extensions
of the valve, said armatures arranged to
swing in an arc eccentric to the curve of the
extended poles and having their greatest at-
traction at the beginning of their movement 95
and the least at the end of their movement,
substantially as and for the purpose described.

5. In an electric-lighting apparatus, as de-
scribed, the combination, with the gas-burner
tube T, having a flange O, of the electro-mag- 100
nets A A², the valve E, the armatures C C²,
the levers D D² X X², pivoted on the axial
extensions of the valve, said armatures held
to normally engage the tube T and the flange
O when swung up, said tube and flange hav- 105
ing sound-deadening means at such contacts,
all as and for the purpose described.

In testimony whereof we affix our signatures
in presence of two witnesses.
